[57] **CLAIM**

The ornamental design for an outdoor information kiosk, as shown and described.

DESCRIPTION

FIG. 1 is a front elevational view of an outdoor information kiosk showing my new design for said outdoor information kiosk;

FIG. 2 is a rear elevational view thereof;

FIG. 3 is a right side elevational view thereof;

FIG. 4 is a left side elevational view thereof;

FIG. 5 is a top view thereof; and,

FIG. 6 is a left front perspective view thereof.

In FIGS. 1 and 6, the broken lines showing a screen of a computer monitor set behind the front panel of the information kiosk is for illustrative purposes only and forms no part of the claimed design.
